UNITED STATES PATENT OFFICE.

MARTIN H. MOSMAN, OF WATERBURY, CONNECTICUT.

DESIGN FOR A FORK AND SPOON HANDLE.

Specification forming part of Design No. 6,577, dated April 8, 1873; application filed January 25, 1873.

To all whom it may concern:

Be it known that I, MARTIN H. MOSMAN, of Waterbury, in the county of New Haven and State of Connecticut, have invented a new and original Design, of which the following is a specification:

This invention relates to a new configuration of the handle of a fork or spoon or similar article, and also to a new ornamentation of their surfaces.

In the accompanying drawing, Figure 1 represents a face view of a fork of which the handle is made in my improved design, and Fig. 2 is a face view of the lower part of a fork-shank made of the ordinary well-known shape.

The first part of my invention consists in a new outline or profile form of the tip *a*, head *b*, and shank *d*, and breast *e* of a fork or spoon handle. The tip is pointed and has slightly curved edges which meet the concave sides of the head, of which the lower ends connect by further concave edges with the straight, or nearly straight, edges of the shank *d*, as shown.

As to the cross-section of the edges of the head, shank, or tip, I do not confine myself to any particular shape, as the same may be rounded or entirely flat, beveled or threaded, or otherwise formed in suitable manner.

The breast *e*, or connection between the shank and fork-blank or tines, is in form of a plain

concave curve, as is clearly shown in Fig. 1, thus producing a sharp edge at the junction of the breast and blank or tines. The effect thus produced is original and beautiful.

The second feature of my invention refers to the ornamentation of the face of the handle, the same being made in three principal groups, the upper group *g* being in the tip, the middle group *h* in the lower part of the head, and the lower group *i* in the upper part of the breast. The tip ornament *g* is composed of a trefoil held in a semi-oval point or crown. The head ornament *h* is of similar style, but reverse in position to that of the tip ornament, so that the trefoils will point toward each other, and has a further trefoil suspended below the semi-oval point toward the shank, as shown. The breast ornament *i* is also in form of a trefoil, but elongated and provided with two additional leaves, the upper semi-oval being above the points or leaves, as shown.

Claim.

1. The design for the outline of the fork or spoon handle, as shown.
2. The design for the ornamentation of the face of the fork and spoon handle, as shown.

M. H. MOSMAN.
